UNITED STATES PATENT OFFICE.

SAMUEL GREENES, OF POUGHKEEPSIE, NEW YORK.

GARMENT.

No. 889,877.

Specification of Letters Patent.

Patented June 2, 1908.

Application filed January 29, 1908. Serial No. 413,183.

To all whom it may concern:

Be it known that I, SAMUEL GREENES, a citizen of the United States, and a resident of Poughkeepsie, in the county of Dutchess 5 and State of New York, have invented a new and Improved Garment, of which the following is a full, clear, and exact description.

My invention relates to garments, my more particular purpose being to produce a 10 garment provided with openings so secured by fastenings as to render the size of the garment, to some extent, adjustable at will, and so arranged that the garment is reversible, presenting to the eye a constructional difference 15 in appearance when viewed upon one of its sides, as compared with the view presented from the other side.

Reference is to be had to the accompanying drawings forming a part of this specification, in which similar characters of reference indicate corresponding parts in all the figures.

Figure 1 is a front elevation showing the garment upon the person, and so worn that the lacing cords are visible and may be manipulated from the outside of the garment for the purpose of increasing or decreasing the size of the garment; Fig. 2 is a fragmentary elevation showing the back of the garment, and also showing the garment so turned that the lacing cords may be seen from the outside; Fig. 3 is an enlarged fragmentary plan of a portion of the garment, showing the same as folded so as to form an opening covered by a plait, and further 35 showing the lacing cord for adjusting the size of the opening; Fig. 4 is a diagrammatic section through the upper portion of the garment, showing how the lacing cords are distributed in order to enable the operator to 40 vary, within limits, the size of the garment, this view further showing how the plaits are concealed inside the garment when it is desired to show the cords outside of the same; and Fig. 5 is an enlarged fragmentary section 45 through one of the plaits and the embroidered lacing holes disposed adjacent to opposite edges of the plait.

The body of the garment is shown at 6, the neck portion at 7, a hood at 8, this hood 50 being mounted upon the upper portion of the garment for the purpose of partially encompassing the wearer's head, and at 9 is a cape

connected permanently with the body portion. At 10 are plaits made by folding the body portion back upon itself, as indicated 55 in Fig. 5, the folds 11 being sewed and provided with worked holes 13 for receiving a lacing cord 12, as will be understood from Figs. 3 and 5. The folds 11 are thus separated by an opening 6^a, and by loosening or 60 tightening the cords 12 the folds 11 may be allowed to move apart or be drawn toward each other, as the case may be. This renders the garment adjustable within wide 65 limits.

The neck portion 7 is not changed, and the bottom portion, because it hangs loosely, can readily accommodate itself to persons of different sizes, but the upper portion of the garment, adjacent to the wearer's shoulders, 70 may be extended or contracted at will by simply changing the tightness of the cords 12.

As there are four different openings 6^a, the effects of adjusting the garment are distributed equally upon four different portions 75 of the garment. That is to say, the garment, as a whole, may be adjusted within wide limits, yet no particular opening 6^a need be changed greatly in size, for the reason that there are several such openings and the spacing may be rendered equal in all of them, At 14 is a plait in the back of the garment.

This garment is reversible. When worn as indicated in Fig. 1, the cords 12, being upon the outside, are visible. If, however, 85 the garment be turned, the plaits 10, being upon the outside, conceal the cords 12. This gives the garment a different appearance according as one side or the other may be worn outwardly.

The appearance of the plaits 10 presents such a marked contrast to the appearance of the cords 12 laced through the worked holes 13, that the garment, for many purposes, serves practically as two distinct garments. 95

Having thus described my invention, I claim as new and desire to secure by Letters Patent:

In a garment, the combination of a body portion folded upon itself so as to form a 100 number of plaits, said plaits being spaced substantially equidistant, said garment being provided, adjacent to each of said plaits, with a plurality of holes disposed upon oppo-

site sides of the plait, and a lacing member threaded through said holes for the purpose of contracting and enlarging said garment at the plaits, said garment being reversible so that when worn in one position said lacing member is visible, and when worn in another position said lacing member is concealed.

In testimony whereof I have signed my name to this specification in the presence of two subscribing witnesses.

SAMUEL GREENES.
